UNITED STATES PATENT OFFICE.

GEORGE W. DEARBORN, OF BOSTON, MASSACHUSETTS.

FAN ATTACHMENT FOR ROCKING-CHAIRS.

SPECIFICATION forming part of Letters Patent No. 597,177, dated January 11, 1898.

Application filed June 18, 1897. Serial No. 641,305. (No model.)

To all whom it may concern:

Be it known that I, GEORGE W. DEARBORN, a citizen of the United States, residing at Boston, in the county of Suffolk and State of Massachusetts, have invented certain new and useful Improvements in Fan Attachments for Rocking-Chairs, of which the following is a specification, reference being had therein to the accompanying drawings.

10 My invention relates to fan attachments for rocking-chairs having a pivoted fan-carrier adapted to be oscillated as the chair rocks by a pendulum or counterpoise.

15 The invention relates more particularly to the detail arrangement of the fan-handle holder, whereby a universal adjustment thereof is obtained, and to the means for pivoting the fan-carrier to a single supporting standard.

20 The invention also includes other details of construction, as will be hereinafter described, and particularly pointed out in the claims.

25 The attachment is illustrated in the accompanying drawings, in which—

Figure 1 is a side elevation of the attachment; Fig. 2, a rear view of the same. Fig. 2^a is an enlarged detail view, and Fig. 3 a detail view of a modification.

30 In the present device I aim to utilize only a single standard (shown at *a*) provided with an inwardly-curved upper end and having its lower end adjustably held in the socket-plate *b*, which is permanently secured to the rear upper bar of the rocker.

35 A sleeve *c* is brazed or otherwise secured in the extreme upper end of the standard *a* and extends transversely of the same on each side thereof. This provides a bearing for the journal *d*, which extends laterally from the intermediate portion of the arm *e*, carrying a weight *g* at its lower end and having its upper portion curved inwardly and extended horizontally and carrying the fan-handle holder, as will be hereinafter described. The journal *d* extends almost entirely through the sleeve *c* and has a threaded socket bored in its end, into which the shank of a bolt *h* screws, said bolt having a head which bears

40 upon the end of the sleeve *c* and thus holds the journal in place. At the beginning of the horizontal part of the arm *e* a collar or

flange *i* is located, against which one end of a spring *l*, coiled around said arm, bears, the opposite end of said spring bearing against 55 a sleeve *l'*, loose on the horizontal part of the arm and holding the same in frictional contact with a washer held to the extreme end of the arm by a screw *o*. A boss is formed on one side of this sleeve, to which is pivoted 60 one member of an L-shaped clip or elbow *r*, the other member having a plate *s* secured thereto.

There is sufficient frictional contact between the clip *r* and the boss in the sleeve to 65 prevent the clip from moving accidentally when once set manually to a predetermined position.

The plate *s* forms the backing to receive the fan-handle, and the handle is clamped 70 thereto by the springs *u v*, the spring *u* having its lower end bent laterally and secured to the back of the plate near its lower end, the main part of said spring lying parallel with the edge of said plate and the upper 75 portion being free and looped so as to extend across the front of the plate. The spring *v* corresponds to the spring *u*, its lateral end, however, being secured to the upper part of the plate. The fan-handle is inserted between the loops and the plate and is thus securely held in place.

It will be apparent from the foregoing description that the fan may, while held in place, be adjusted to any position around the horizontal extension of the arm by turning the sleeve *l'* thereon, or said fan may be adjusted in a plane parallel with said arm on the pivot of the clip *r*. The sleeve *l'* and spring may be dispensed with and the clip *r* be secured 90 directly to the arm, and a second clip carrying the plate *s*, corresponding to the first, may be pivoted to the outer member of said first clip. The springs *u* and *v* may also be dispensed with and in place of the same a spring- 95 loop having its ends fixed to the opposite edges of the plate *L* may be provided. To the center of this loop, which extends across the plate *L*, a plate *i* is secured, this latter plate corresponding in contour to the plate *L*; but 100 it is preferably of less length than the same.

The handle of the fan is adapted to be held between the opposing faces of the two plates.

I claim—

1. In combination, the standard, the arm pivotally secured thereto, having a horizontal portion, the weight fixed to the lower end of said arm, the sleeve on the horizontal portion 5 of the arm with frictional means for holding the same, an elbow having one member pivoted to said sleeve, a plate fixed to the other member of said elbow and the means for clamping the fan-handle to the plate.
2. In combination, the standard, the arm pivotally secured thereto, the collar or flange on said arm, the washer on the end of the arm, the sleeve interposed between said collar and washer, the spring coiled around said 15 arm and interposed between the collar and sleeve to hold the sleeve in frictional contact with the washer, the elbow having one end pivoted to the sleeve, the plate pivoted to the other member, and the spring clamping-loop 20 secured to said plate.

3. In combination, the socket-plate secured to the chair-back, the standard adjustable therein and having its upper end inwardly curved the arm having a weighted lower end

and a curved upper end with a horizontal extension, a journal extending laterally from the intermediate part of the arm, a sleeve secured in the extreme curved end of the standard and projecting laterally on opposite sides thereof and forming a bearing for said journal, means for retaining the journal in the sleeve, the collar on the arm located at the beginning of the horizontal extension, a washer held to the extreme end of the arm, a sleeve on said arm between the collar and washer, a coiled spring interposed between the collar and the sleeve for holding the latter into frictional contact with the washer and the fan-handle holder pivotally secured to said sleeve, said holder having looped 40 spring-retainers.

In testimony whereof I affix my signature in presence of two witnesses.

GEORGE W. DEARBORN.
